UNITED STATES PATENT OFFICE.

LEE DE FOREST, OF NEW YORK, N. Y., ASSIGNOR TO DE FOREST RADIO TELEPHONE AND TELEGRAPH COMPANY, OF NEW YORK, N. Y., A CORPORATION OF DELAWARE.

RADIOTELEPHONY.

1,314,251.

Specification of Letters Patent. Patented Aug. 26, 1919.

Application filed March 11, 1915. Serial No. 13,573.

To all whom it may concern:

Be it known that I, LEE DE FOREST, a citizen of the United States, and residing in the city, county, and State of New York, 5 have made a certain new and useful Invention in Radiotelephony, of which the following is a specification.

This invention relates to radio telephony.

The object of the invention is to provide 10 improved means for efficiently varying the high frequency energy employed in wireless telephony in accordance with sound waves.

A further object of the invention is to provide a system of radio telephony whereby 15 the range of transmission and reception is increased.

Other objects of the invention will appear more fully hereinafter.

It is well known in radio telephony, and 20 particularly where it is desired to send messages through great distances, a large amount of high frequency energy must necessarily be radiated. The chief difficulty heretofore encountered has been in trying to vary the 25 large amounts of high frequency energy required in accordance with the sound waves. In addition, for successful operation for long range radio telephony, telephone transmitters or "microphones" of such strength 30 as to control from 10 to 50 amperes of current, and still retain their sensitiveness to voice vibrations have been necessary. Various methods of constructing and operating telephone transmitters to control the required 35 current have been proposed and tried, such as by employing a large number of carbon transmitters connected in series parallel arrangement and cooling the same in various ways, but none of the proposed methods 40 have proved sufficiently efficient. Either the heating and rapid destruction of the transmitters or "microphones" results or the voice controlled devices are quite inadequate to control or to sufficiently vary the very 45 large amounts of energy required to permit reception at great distances of the comparatively slight current fluctuations which these devices produce.

For long distance radio telephony it is 50 necessary to produce variations in the amplitude of the radiated wave-trains of from 50 to 100 per cent. of the total amount of energy received, and if it be attempted to introduce a resistance-varying device directly in the 55 antenna-earth circuit of the transmitter sys-

tem, this device must be capable of controlling from 10 to 50 kilowatts of energy and of dissipating a very large percentage of this entire energy in heat.

It is among the special purposes of my 60 present invention to provide arrangements for enabling long distance radio telephonic communications wherein it is not necessary to consume a large percentage of the normally radiated energy in voice actuated resistance devices, but merely to sufficiently alter the wave length of the radiated wave-train to produce in the sharply tuned circuit at the distant receiving station, changes in the amount of the energy received which 70 shall be directly proportional to the changes in resistance of the voice actuated transmitter at the sending station.

I have found that if a "microphone" be connected in shunt to a portion of the inductance of the transmitter system, the energy which is thus shunted through the microphone will be proportional to the amount of inductance in the shunt circuit, and inversely proportional to the resistance of the 80 microphone itself and its leads. This resistance, however, must be kept comparatively low, as any ordinary microphone device which is capable of faithfully reproducing in resistance changes the fluctuations 85 of the voice can only safely consume from 100 to 500 watts. However, if the microphone be connected in shunt to too large an inductance, the potential drop across its electrodes becomes so great that pernicious 90 arcing occurs which not only rapidly destroys the microphone but results in great distortion of the voice effects, and the device is apt to "pack" or cohere, in which case it rapidly becomes unresponsive to the voice, 95 unless special means are provided to prevent this result. If, on the other hand the microphone is connected across too small a part of the total inductance of the transmitter circuit, the foregoing harmful effects are 100 avoided, but the effect then on the alteration of the wave length of the radiated waves becomes too small to be perceptible at a distance even in the most sharply tuned receiving circuits. I have discovered, however, 105 that by combining a number of such microphones or voice transmitting devices and connecting each of them directly in shunt across a small portion of the total inductance and actuating all of these microphones 110

or voice transmitters "in phase" with each other, by the voice or by voice controlled means, it is possible to thus "detune" a large power radiating system without harmful effects upon the transmitter devices themselves, and to thus produce large fluctuations in the energy received by a distant sharply tuned receiving system, in close simulation of the original voice, or sound waves.

10 Various arrangements for carrying out my discovery in practice may be employed, and in the accompanying drawings I have shown various arrangements for accomplishing the desired results.

15 Referring to the drawings,

Figure 1 shows a simple diagrammatic arrangement embodying my invention.

Fig. 1^a is a view showing one form of a sharply tuned receiving system.

20 Figs. 2, 3, and 4 show diagrammatically alternative transmitting arrangements embodying my invention.

The same part is designated by the same reference numeral through the several views.

25 Referring to Fig. 1, I have shown an exceedingly simple arrangement for accomplishing the objects and purposes of my invention wherein I employ the usual radiating antenna 1 of a transmitting system

30 which is connected to ground 2 through the usual variable load inductance 3 and the source of high frequency energy, indicated in this instance at 4. In this form of my invention I propose to employ an additional inductance 5 which is of from 3 to 5 per cent. of the total inductance in the antenna-earth circuit. Three or more microphone transmitters, according to the number of turns employed in the additional inductance

35 5, designated at 6, are each connected across a proportional amount of the inductance 5. In this case, where three microphones are employed, each one of them is connected across one third of the total inductance of 40 the coil 5. Reference numeral 7 designates a diagrammatic illustration of a mouth-piece as generally employed in telephonic apparatus into which are delivered the sound waves to be reproduced at the distant station. These sound waves, in the arrangement shown, influence or affect to equal extent the microphones 6.

45 In Fig. 1^a I have shown one form of a sharply tuned receiving circuit suitable for use in connection with my invention wherein 1, 3, 8, 9, 2 are the antenna, inductance, variable capacities and earth or ground of a well known tuned receiving circuit. An audion 10, is connected across the "coupling" condenser 8, in the usual and well known manner, and a small stopping condenser 11 is connected in series between the antenna connection and the grid element of the audion. 13 and 14 designate the two usual batteries 50 of the audion wing and filament circuits, 12

designates the variable resistance for regulating the current in the filament circuit. The receiver, in the arrangement shown, is connected in the wing or plate circuit of the audion, preferably between the wing or plate and the battery 13, as diagrammatically illustrated at 15.

In Fig. 2 I have shown a transmitting system similar to Fig. 1 wherein the microphone transmitters are connected across the 75 equal portion of the auxiliary inductance 5, but the diaphragms 16 of the microphones are each actuated by an electromagnet 17. The coils of these electromagnets may be connected in any desired relation. I have 80 shown them connected in series with each other and in series with a variable condenser 18 and with an alternating current generator 19, having a frequency above that of the more essential frequency of the sound 85 waves of the human voice. It is evident that when the inductance and capacity of the circuit 19, 18, 17, are made such that its natural period coincides with that of the frequency of the alternating current generator 90 19, the diaphragms 16 are maintained in continuous rhythmic vibration or fluctuation in the frequency and amplitude of the radiated waves, but at a rate too high to produce a disturbing sound in the telephonic receiver 95 at the distant receiving station. This periodic agitation of the microphone devices 16, 17, prevents them from "packing" and at the same time greatly facilitates the control of the amplitude of their vibrations by means 100 of the sound waves directed against the "master" microphone transmitter, indicated at 20. This "master" microphone 20, is connected in shunt across the generator 19, or across the electro-magnets 17, as shown.

105 In Fig. 3 I have shown the usual antenna-earth system shown and described in connection with the preceding figures, and a series of sensitive conducting gas flames 33 is arranged to play between the fixed electrodes 31, 32, which are connected to their respective coils of the inductance 3, thereby making the air gaps between the electrodes 31, 32, a conducting medium and tending to short circuit the coils of the inductance 3. 110 As shown, these gas burners may be supplied from a common source through a tube 34. The gas passes through a small chamber 35 one side of which is closed by a flexible diaphragm 36 against which the sound waves of the voice or sound source is directed through the usual mouth piece 7.

115 In Fig. 4 I have shown the usual transmitting antenna-earth system with the auxiliary inductance 5 wherein the voice controlled resistance devices are mercury vapor discharge tubes 46, each connected across one turn of the auxiliary inductance 5 at the base of the antenna-earth system. The vapor columns are deflected, and the resist- 120 125 130

5 ance of the shunting circuits thereby altered by means of the electromagnets 17, placed in proximity to the discharge tubes, and operating as described in Fig. 2, the solenoids 5 being shown in this instance as connected in series and in series with a source of current 50 and the master microphone 20.

10 While I have shown mercury vapor tubes, my invention is not to be limited or restricted in this respect.

15 It will be seen that I have supplied a means and apparatus for use in radio telephony that permits the alteration of the wave length of the radiated wave trains at the transmitting station to produce changes in the amount of energy received at a distant receiving station which are directly proportional to the changes in the resistance of the voice or sound actuated devices at the sending station, and it is obvious that it is thereby possible to send telephonic communications over very great distances without encountering the disadvantages or objections that heretofore so far as applicant is aware 20 that heretofore so far as applicant is aware 25 has made long distance telephonic communication unsatisfactory and expensive.

Having now set down the nature and purposes of my invention, and having shown and described various means and circuit arrangement for accomplishing the objects and embodying my invention, what I claim as new and useful and desire to secure by Letters Patent of the United States, is,—

1. In a radio telephone transmitting system, an inductance and a plurality of resistance varying devices, each connected in shunt around a relatively small portion of said inductance and means for simultaneously maintaining all of said resistance varying devices in continuous vibration.

2. In a radio telephone transmitting system, an inductance and a plurality of resistance varying devices, each connected in shunt around a relatively small portion of

said inductance and a source of alternating 45 current to simultaneously maintain all of said resistance varying devices in continuous vibration.

3. In a radio telephone transmitting system, an inductance and a plurality of resistance varying devices, each connected in shunt around a relatively small portion of said inductance and means including a source of alternating current having a frequency above that of the more essential frequencies of the human voice, for maintaining said resistance varying devices in continuous vibration.

4. In a radio telephone transmitting system, an inductance and a plurality of resistance varying devices, each connected in shunt around a relatively small portion of said inductance and means including a source of alternating current to maintain all of said resistance varying devices in continuous vibration and means for controlling the amplitude of said alternating current by sound waves.

5. In a radio telephone transmitting system, an inductance and a plurality of resistance varying devices, each connected in shunt around a relatively small portion of said inductance and means including a source of alternating current having a frequency above that of the more essential frequencies of the human voice, for maintaining said resistance varying devices in continuous vibration and means for controlling the amplitude of said alternating current by sound waves.

In testimony whereof I have hereunto set my hand in the presence of the subscribing witnesses, on this 2nd day of March A. D., 1915.

LEE DE FOREST.
